UNITED STATES PATENT OFFICE.

JOSEPH H. SARIS, OF BELOIT, WISCONSIN.

CARBURETER FOR LIQUID-FUEL ENGINES.

SPECIFICATION forming part of Letters Patent No. 747,235, dated December 15, 1903.

Application filed April 15, 1903. Serial No. 152,748. (No model.)

To all whom it may concern:

Be it known that I, JOSEPH H. SARIS, a citizen of the United States, residing at Beloit, in the county of Rock and State of Wisconsin, have invented a certain new and useful Improvement in Carbureters, of which the following is a full, clear, concise, and exact description, reference being had to the accompanying drawings, forming a part of this specification.

My invention relates to carbureters and is of particular service in connection with the operation of engines operated through the agency of liquid fuel that is gasified or carbureted. Hitherto carbureters have been adapted to effect mixture of air and fuel in a substantially fixed ratio and in a quantity proportionate to the speed of the engine above a given lower limiting speed. It is well understood that carbureters employed in connection with engines are provided with a chamber adapted for communication with the cylinder of the engine and also with an oil-supply, in which chamber there is provided a piston that is fixed with respect to a valve that controls the admission of fuel through a valve-opening. This chamber is provided with an orifice or orifices, usually at its bottom portion, through which air is passed by the force of suction due to the operation of the piston within the engine-cylinder, which action of suction also serves to operate the piston within the chamber of the carbureter to open the valve-passage to permit ingress of the liquid fuel, the valve being adapted to seat itself when the force of suction is absent, a spring being desirably employed to aid gravity in order that the valve may thus be seated. The inrushing air and the admitted fluid fuel are intermixed within the said chamber and drawn into the operating-cylinder of the engine through the agency of the engine's piston. It will thus be obvious that the only regulation of the liquid or oil supplied to the chamber of the carbureter in the prior devices here described was due to the operation of the piston within the engine-cylinder and that the tendency was to maintain a fixed ratio of oil and air in the intermixing process. In practice it is well known that in carbureters of this description when the speed of the engine falls below a pre-

terminated speed the mixture of oil and air would not be sufficiently rich to operate the engine at such low speed.

It is the object of my invention to provide means whereby the proportion of oil supplied to the mixing-chamber of the carbureter will be enlarged when the speed of the engine is reduced and whereby the extent of the increase of the oil-supply to the mixing-chamber of the carbureter may be regulated. Generally speaking, my invention resides in means for modifying the ratio of fuel or oil supplied through the valve-opening governed by the operation of the valve. In the preferred embodiment of my invention this means resides in a continuation of the valve, which is provided with a bore constituting a continuation of a bore provided in the valve, whereby when the speed of the valve is reduced the oil, finding passage through the valve-opening, will when the valve is seated also find passage in the bore therein, and when the valve is elevated the oil passing through the main valve-opening and admitted to the chamber directly therefrom will also be added to by the oil previously accumulated in the bore in the valve. When the vibration of the valve is very rapid, as when the engine is operating at a high rate of speed, the oil will have small opportunity to climb within the valve bore or channel, and hence the oil admitted through the main valve-opening will not then be materially added to. I prefer to employ adjusting means whereby the initial rate of flow of the fluid fuel through the valve-opening may be regulated to correspond to the highest speed of the engine and additional means whereby the size of the passage or channel through the valve and its stem may be regulated to determine the quantity of oil that may be passed into the channel when the valve is seated, the rate of this flow into the valve-channel being in proportion to the lowest speed at which it is desired to have the engine operate.

I will explain my invention more fully by reference to the accompanying drawings, in which—

Figure 1 is a view in sectional elevation of the preferred form of a carbureter embodying my invention. Fig. 2 is a detail view, in sectional elevation, of my improved form of

valve structure. Fig. 3 is a sectional plan view of a portion of the carburetor on line 33 of Fig. 1. Fig. 4 is a sectional plan view of a portion of the carburetor on line 44 of Fig. 1.

5 Like parts are indicated by similar characters of reference throughout the different views.

At the right-hand portion of Fig. 1 I have indicated a part of an engine-cylinder *a*, 10 which supports the entire carburetor, a pipe *b* desirably forming a continuation of a mixing-chamber *c* to afford communication between the said mixing-chamber and the cylinder of the engine. A segmental valve *d* is 15 provided within the mixing-chamber and has a cap-wall *e*, from which extends the stem *f*, to which stem the handle *g* is attached, so that the extent to which the engine-cylinder may have communication with the mixing- 20 chamber is regulable. The stem *f* is hollow to receive a valve-stem *h*, that is adapted to freely reciprocate back and forth with respect to the stem *f* as the piston within the engine-cylinder reciprocates. The valve-stem *h* terminates in or carries the main valve *i* of the 25 carburetor and also carries a piston *k*, that desirably loosely fits the mixing-chamber and which is preferably perforated at *l*, which perforations are covered by a screen *m*. As 30 the piston within the engine-cylinder reciprocates suction due to the engine-piston forces the elevation of the piston *k*, and with it the main valve *i*, whereupon oil or other fluid fuel from a source of supply *n* may find 35 passage through the duct *o* and the valve-opening *p*. When the piston is on its return stroke, suction is absent and the valve *i* will lower, being desirably aided by means of a coil-spring *q*, that may be interposed between 40 the cap-wall *e* and a shoulder *r* upon the stem *h*. The mixing-chamber is provided with a continuation *s*, that extends below the stem and which may be provided with a draft-regulator *t*, provided with openings that may 45 be brought either into or out of register with the openings provided in the bottom wall of the continuation *s*, as desired. It will be understood that this continuation *s* is in communication with the engine-cylinder, as well 50 as the balance of the chamber, as the valve-opening *p* is provided in a bridge or rib *u*, that extends across the mixing-chamber, but does not close the same. A screen *v* is located 55 above the rib. Any suitable means for supplying the oil may be provided, there being illustrated a chamber *n*, having therein a float *w*, serving to maintain the oil above the level of the valve-opening, so that when the valve *i* is unseated the oil will readily find 60 passage within the mixing-chamber. A regulating set-valve *x* is provided for determining the rate of flow through the valve-opening *p*, the regulating-valve being set to correspond to the highest speed at which 65 the engine is to operate. The admission-valve *i* is provided with a channel *y*, that extends from the bottom thereof and which

is continued through its stem, at the upper end of which it is branched at *y'* to afford communication with the exterior atmosphere 70. The extent of the communication of the channel within the valve with the external atmosphere is regulated by means of the needle-valve *z*, that is contained within an enlarged portion of the channel *y* and which is threaded 75 at its upper end to have engagement with a threaded nut or collar *z'*, so that the longitudinal position of the said valve with respect to the valve-stem *h* after having been adjusted may be maintained, the adjustment 80 being effected by reason of the threaded engagement had between the needle-valve and the valve-stem *h*.

It will be obvious that if the channel in the valve were not continued through the stem 85 or otherwise open the oil would rise to no appreciable extent within the valve and that if no regulating means, as the needle-valve, were employed it would be difficult to properly proportion this channel to varying 90 requirements. The operation of the mechanism will be clearly understood. When the engine is operating at a high rate of speed, the reciprocation of the valve *h* is correspondingly rapid, the valve *h* being seated 95 for such small fractions of time as to prevent the oil from rising within the channel therein, in which condition of things the rate of oil-supply is that which has been mainly determined by the regulating-valve *x*. If now 100 the speed of the engine drops materially, the valve *h* will remain seated longer, permitting the oil to rise within the channel therein, so that when the valve is unseated this oil will be discharged into the mixing-chamber to 105 supplement the oil that is admitted through the main valve-opening, the mixture being correspondingly enriched, as is required to effect the operation of the engine at such lower 110

I have herein shown the preferred construction of carburetor constructed in accordance with my invention; but I do not wish to be limited to the precise features shown, as changes may readily be made without departing from 115 the spirit of my invention; but,

Having thus described my invention, I claim as new and desire to secure by Letters Patent—

1. In a carburetor, the combination with the 120 mixing-chamber thereof having a fuel-duct leading thereto and also a valve-opening in communication with the said fuel-duct, of a piston within the mixing-chamber, a valve carried by the piston, a stem constituting a 125 continuation of the valve, an air-channel passing through the valve and stem for communication with the valve-opening, a regulating-valve for determining the effective size of the said air-channel and a set-valve for 130 regulating the initial flow of fluid fuel through the fuel-supply duct, substantially as described.

2. In a carburetor, the combination with the

mixing-chamber thereof having a fuel-duct leading thereto and also a valve-opening in communication with the said fuel-duct, of a piston within the mixing-chamber, a valve carried by the piston, a stem constituting a continuation of the valve, an air-channel passing through the valve and stem for communication with the valve-opening, and a regulating-valve for determining the effective size of the said air-channel, substantially as described.

3. In a carbureter, the combination with the mixing-chamber thereof having a fuel-duct leading thereto and also a valve-opening in communication with the said fuel-duct, of a piston within the mixing-chamber, a valve carried by the piston, a stem constituting a continuation of the valve, an air-channel passing through the valve and stem for communication with the valve-opening, and a set-valve for regulating the initial flow of fluid fuel through the fuel-supply duct, substantially as described.

4. In a carbureter, the combination with the mixing-chamber thereof having a fuel-duct leading thereto and also a valve-opening in communication with the said fuel-duct, of a piston within the mixing-chamber, a valve carried by the piston and a stem constituting a continuation of the valve, an air-channel passing through the valve and stem for communication with the valve-opening, substantially as described.

5. In a carbureter, the combination with the mixing-chamber thereof having a fuel-duct leading thereto and also a valve-opening in communication with the said fuel-duct, of a piston within the mixing-chamber, a valve carried by the piston, an air-channel passing through the valve for communication with the valve-opening, and a set-valve for regulating the initial flow of fluid fuel through the fuel-supply duct, substantially as described.

6. In a carbureter, the combination with the mixing-chamber thereof having a fuel-duct leading thereto and also a valve-opening in communication with the said fuel-duct, of a piston within the mixing-chamber, a valve carried by the piston and an air-channel passing through the valve for communication with the valve-opening, substantially as described.

7. In a carbureter, the combination with the mixing-chamber thereof having a fuel-duct leading thereto and also a valve-opening in

communication with the said fuel-duct, of a piston within the mixing-chamber, a valve carried by the piston, an air-channel passing through the valve for communication with the valve-opening, a set-valve for regulating the initial flow of fluid fuel through the fuel-supply duct and means for regulating the effective size of the air-channel through the valve, substantially as described.

8. In a carbureter, the combination with the mixing-chamber thereof having a fuel-duct leading thereto and also a valve-opening in communication with the said fuel-duct, of a piston within the mixing-chamber, a valve carried by the piston, an air-channel passing through the valve for communication with the valve-opening, and means for regulating the effective size of the air-channel through the valve, substantially as described.

9. In a carbureter, the combination with the mixing-chamber thereof, of a reciprocating valve for controlling the admission of fuel into the mixing-chamber, the said valve being provided with a channel therethrough to receive more or less oil for fuel when seated, according to the rate of its reciprocation to effect the corresponding increase of the fuel admitted to the mixing-chamber, and means for regulating the effective size of said channel, substantially as described.

10. In a carbureter, the combination with the mixing-chamber thereof, of a reciprocating valve for controlling the admission of fuel into the mixing-chamber, the said valve being provided with a channel therethrough to receive more or less oil for fuel when seated, according to the rate of its reciprocation to effect corresponding increase of the fuel admitted to the mixing-chamber, substantially as described.

11. In a carbureter, the combination with a mixing-chamber thereof having a duct leading thereto, means for admitting varying quantities of fuel from the said duct to the said mixing-chamber, and a piston carrying the said means serving to govern the rate of operation of the said means by the rate of its reciprocation, substantially as described.

In witness whereof I hereunto subscribe my name this 6th day of April, A. D. 1903.

JOSEPH H. SARIS.
